FIG. 1.

FIG. 2.

FIG. 3.

FIG. 4.

The dominant features of my design reside in the portions shown in full lines, the broken line representation of indicia being omitted from FIGURES 2 and 3 for convenience of illustration.

I claim:

The ornamental design for a sign or similar article, as shown and described.
